Specification for Design.

Patented Nov. 20, 1917.

Application filed October 4, 1917. Serial No. 194,827. Term of patent 7 years.

To all whom it may concern:

Be it known that I, HARRISON HEBBARD, a citizen of the United States, and a resident of East Orange, in the county of Essex and State of New Jersey, have invented a new, original, and ornamental Design for a Tray, Dish, or Similar Article of Silver Hollow Ware, of which the following is a specification, reference being had to the accompanying drawing, forming a part thereof.

Fig. 2 is a side elevation.

Fig. 3 is a vertical fragmentary section on the line 3—3 of Fig. 3 looking in the direction of the arrows.

I claim:

The ornamental design for a tray, dish, or similar article of silver hollow ware as shown.

HARRISON HEBBARD.
